UNITED STATES PATENT OFFICE.

FREDRIK LJUNGSTRÖM, OF LIDINGO-BREVIK, AND BIRGER LJUNGSTRÖM, OF STOCKHOLM, SWEDEN, ASSIGNEES TO AKTIEBOLAGET LJUNGSTRÖMS ANGTURBIN, OF STOCKHOLM, SWEDEN, A CORPORATION.

AIR-COOLED CONDENSER.

Application filed August 21, 1922. Serial No. 583,460.

To all whom it may concern:

Be it known that we, FREDRIK LJUNGSTRÖM and BIRGER LJUNGSTRÖM, both subjects of the King of Sweden, and residing, respectively, at Lidingo-Brevik, Sweden, and Stockholm, Sweden, have invented certain new and useful Improvements in Air-Cooled Condensers, of which the following is a specification.

10 In condensers for locomotives it has previously been suggested to construct the same of flattened pipes through which the steam is passed and condensed by means of air forced about the cooling elements. It has 15 also been proposed to place such elements at right angles to the running direction of the train and to divide them into groups, each cooling element being provided with pressed up ribs or the like. When the cooling elements are placed at right angles to the running direction it is difficult to give them sufficient rigidity so that they may be able to 20 sustain the stresses arising from the varying speed of the locomotive. Supposing the locomotive to possess a certain velocity which is suddenly braked, the elements placed at right angles to the running direction and only fixed at both ends will bend in the middle owing to the inertia, and on 25 account of this action there will be a danger of the elements or their fastening devices on the steam pipes of the condenser being deformed and leaks occurring in the condenser.

Each cooling element consisting of a flattened pipe is in well-known manner provided at the sides with lugs or inwardly projecting dents bearing against each other, for the purpose of preventing the elements from being completely flattened. In practice it has however proved difficult to so manufacture the elements as to prevent further flattening of the same under vacuum. Even a slight flattening of each element in the longitudinal direction of the whole condenser will result in a rather considerable play.

This invention relates to an arrangement in such condensers for staying the cooling elements and consists of supports or stays placed parallel or nearly parallel to the elements and between the same and of a stronger construction than the elements. Preferably said supports for the elements

are inserted while the condenser is under vacuum, it being then possible to compress the elements by means of said supports, whereby the elements may be prevented from moving towards each other during the shakings of the carriage.

The accompanying drawings illustrate 60 diagrammatically an embodiment of the invention. Fig. 1 is a section through a condenser stayed in this manner. Fig. 2 is a partial section on the line 2—2 of Fig. 1 on an enlarged scale,

Fig. 3 is an enlarged fragmentary sectional detail of the collecting pipe showing one of the cooling elements supported therein and the connection of the pipe with the adjacent rail,

Fig. 4 is a fragmentary plan view of the invention, and

Fig. 5 is an enlarged vertical sectional detail of the collecting pipe mounted on the rail 10^a and showing one of the supporting 75 stays connected therewith.

Referring to Fig. 1, 1 designates the elements of the air-cooled condenser and 2 a receptacle for water serving in well-known manner as a steam accumulator for the air-cooled condenser and being under vacuum. The exhaust steam of the locomotive enters the receptacle 2 for instance above the level of the liquid, is then conducted through the pipe 3 to the pipe 4 and passes to the elements through collecting pipes 9 attached at ends of the elements and inserted in a rail 9^a which is provided with apertures opening to the steam distributing pipe 4. During the condensation the steam passes 90 downwards through the elements 1 to the collecting pipes 10 mounted on rails which by means of apertures are connected with longitudinally extending pipes 11 connected at one or more points by means of pipes 5 with the condenser receptacle 2. The collecting pipes 10 are attached to the rails 10^a by means of holders 12, and similar arrangements may be provided at the collecting pipes 9.

6 denotes a fan actuating the cooling air necessary for the condensation, the air passing in the direction of the arrow 7. As shown in Figs. 3 and 4, the cooling elements 1 are collected into groups each comprising three elements connected to a 105 common collecting pipe 10. It will appear

from these figures how the elements 1 are provided with pressed up ribs 17.

According to the invention one or more such groups comprising three elements are replaced by a stay consisting of a rigid rectangular pipe 15 or the like filling entirely the space formed by the removal of such a group of elements. Such a stay may preferably be connected with a collecting pipe 10 similar to those of the groups of elements as shown in Fig. 5. In such case the ends of the stays are inserted in apertures in the rails 9^a and 10^a described above, said apertures however not being connected with pipings situated below the same. To further reinforce the elements longitudinally extending connecting pieces or beams 13 are arranged above the elements 1 and 15 and rigidly connected therewith. These connecting elements preferably consist of pieces of flat iron which extend throughout the length of the condenser proper.

What we claim as new and desire to secure by Letters Patent of the United States is:—

25 1. A cooler for locomotive condensers, comprising two rows of collecting pipes, each pipe being provided with openings, cooling elements arranged side by side and extending between said rows of collecting pipes, the opposite ends of each cooling element being inserted in an opening of a collecting pipe of each row and communicating therewith, supporting stays arranged substantially parallel to the elements and between same, and means for maintaining said supporting stays in place between the elements.

40 2. A cooler for locomotive condensers, comprising two rows of collecting pipes, said rows extending substantially longitudinally of the locomotive, each collecting pipe having openings therein, cooling elements arranged side by side and extending between said rows of collecting pipes, the opposite ends of each cooling element being inserted in an opening of a collecting pipe of each row and communicating therewith, and supporting stays arranged substantially parallel to the elements and between same, the opposite ends of each supporting stay

being inserted in an opening of opposed collecting pipes of each row of such pipes.

55 3. A cooler for locomotive condensers comprising two rows of collecting pipes said rows extending substantially longitudinally of the locomotive, each collecting pipe having openings therein, cooling elements arranged side by side and extending between said rows of collecting pipes and divided into a number of groups, the opposite ends of the cooling elements of each group being inserted in an opening of a collecting pipe of each row and communicating with said collecting pipe, and supporting stays arranged substantially parallel to said elements and between said groups of elements, each of said supporting stays corresponding to one of said groups of elements and having the respective ends inserted in opposed collecting pipes of each row of such pipes.

60 4. A cooler for locomotive condensers, comprising two rows of collecting pipes, said rows extending substantially longitudinally of the locomotive, each collecting pipe having openings therein, cooling elements arranged side by side and extending between said rows of collecting pipes, the opposite ends of each cooling element being inserted in an opening of opposed collecting pipes of each row and communicating therewith, supporting stays arranged substantially parallel to the elements and between the same and connecting pieces extending along the condenser for reinforcing said stays.

65 5. A cooler for locomotive condensers, comprising two rows of collecting pipes, each pipe provided with openings, flattened cooling elements arranged side by side and extending between said rows of collecting pipes, the opposite ends of each cooling element being inserted in an opening of a collecting pipe of each row and communicating therewith, and means to keep the elements closely bearing on each other even when vacuum prevails therein.

70 In witness whereof we have hereunto set our hands.

FREDRIK LJUNGSTRÖM.
BIRGER LJUNGSTRÖM.
